UNITED STATES PATENT OFFICE.

EDWARD J. BROOKS, OF EAST ORANGE, NEW JERSEY, ASSIGNOR TO E. J. BROOKS & CO., OF NEW YORK, N. Y.

HAIR-CRIMPER.

SPECIFICATION forming part of Letters Patent No. 314,100, dated March 17, 1885.

Application filed July 22, 1884. (No model.)

To all whom it may concern:

Be it known that I, EDWARD J. BROOKS, a citizen of the United States, residing at East Orange, in the State of New Jersey, have invented a new and useful Improvement in Hair-Crimpers, of which the following is a specification.

This invention relates, as an improvement, to those articles of manufacture designed as substitutes for curl-papers and the like, used by ladies for "crimping" the hair to form curls or ringlets.

The present invention consists in certain improved hair-buttons or "hair-crimpers," hereinafter set forth, each having as a distinguishing characteristic a permanent flexible metallic union between its two "leaves" integral with the metallic frames of said leaves, whereby manufacture is simplified and cheapened and the crimpers are adapted to be easily manipulated; also, in providing such a hair-crimper with a flexible metallic clasp integral with said leaf-frames, for uniting the closed leaves at a point diametrically opposite that at which said flexible metallic union is located, whereby one kind of pressure is secured at both edges, and the pressure upon the hair may be readily regulated by compressing the bent union and clasp more or less; also, in extending said clasp in the form of a tongue, and providing the leaf-frame at the opposite end of the flat crimpler with a catch-opening to receive the same and coat therewith for securely fastening the crimpler; also, in providing the metallic part of such a crimpler with a covering of thin textile fabric, united therewith by a moisture-proof cement, to give the article a desirable finish and preclude injury to the hair by the contact of the metal therewith; also, in providing the lower leaf-frame, from which said clasp projects, with a "ventilating-opening" and bridging the same by said textile covering; also, in providing a metallic part of very thin pliable metal with re-enforcing strips of a stronger pliable metal at its respective bends, either or both, and securing the same by said covering of textile fabric, to combine lightness and strength of bends, as hereinafter set forth and claimed.

Two sheets of drawings accompany this specification as part thereof. Figure 1 of these drawings is a perspective view of one of my hair-crimpers of a simple form closed as in use. Fig. 2 represents a face view of the same flat, as it leaves the factory; and Fig. 2^a, a longitudinal section on the line *x*-*x*, Fig. 2; and Fig. 3 is a perspective view of its metallic and textile parts as they appear before being united. Figs. 4, 5, and 6 represent face views of a similar crimpler with its metallic part made of lead and overlaid or inlaid with strips of stronger metal to re-enforce its bends, either or both. Figs. 7 and 7^a are face views of another crimpler of sheet metal and textile fabric, and the blank of its metallic part, illustrating modifications in mode of manufacture. Fig. 8 is a face view of a larger form, illustrating modifications in size and shape. Fig. 9 is a perspective view of another crimpler closed, and Fig. 9^a a face view of the same flat, illustrating the combination of all the several novel features hereinbefore recited; and Figs. 10 and 10^a are similar views of another crimpler made of round leaden wire; Figs. 11 and 11^a, face views of crimpers flat made from flat leaden wire in a given way; and Figs. 12 and 12^a, face views of crimpers flat made from leaden wire in another way, according to the same invention in part, illustrating additional modifications.

Like letters of reference indicate corresponding parts and their nearest analogues in the several figures.

In the various forms represented by the drawings each of my improved hair-crimpers has metallic frames *a*-*a* for a pair of leaves, with a flexible union, *b*, and a flexible clasp, *c*, integral with the former, and each operates by bending said union *b* so as to bring the leaves one over or upon the other, with the curl of hair which is to be crimped between the leaves, and confining the latter by bending over said clasp *c*, as shown in Figs. 1, 9, and 10.

In the form represented by Figs. 1 to 3, inclusive, the metallic part A, Figs. 2^a and 3, comprising its frames, union, and clasp, is stamped from suitable pliable sheet metal, preferably very thin "taggers tin" of about 100

.48 to .60 gage. Very thin annealed brass may also be used, or rerolled sheet-lead; but crimpers of this form of a given strength made of taggers tin are found to be the cheapest and lightest. Each leaf-frame is stamped with a central opening, *d*, to lighten the article and permit the escape of moisture from the confined hair, and the whole of the metallic part is covered, preferably on both sides, 5 with thin or light woven textile fabric *B*, Figs. 2^x and 3, to bridge said openings and give a desirable finish and non-metallic surfaces to the article, as represented by cross-line shading in Figs. 1 and 2. The blank of 15 said cover is preferably stamped from cloth of the same pattern as the metallic part, but of double length, and each half preferably a little larger than the metallic part, as represented in Fig. 3. This blank is then dipped 20 in a glue, paste, or other cement that perspiration or other moisture will not affect, and its respective halves are then applied to the respective sides of the metallic part, with the fold *e* of the former at that end of the flat 25 crimpler opposite its clasp end. The article is then dried, after which it is ready for immediate use, in the manner aforesaid, or for packing and shipment.

The shape of the crimpler is not considered 30 material, so long as the features above named are preserved; but square or pointed corners should be avoided, as liable to hurt the head.

In the modifications illustrated by Figs. 4 to 6, inclusive, crimpers otherwise identical 35 with the one represented by Figs. 1, 2, and 3, having their said metallic part stamped from sheet-lead rolled very thin, so as to be light enough, are provided between the same and the textile covering represented by cross-line 40 shading with re-enforcing strips *f f*, of taggers tin or like stronger pliable metal, at the clasp *c*, at the union *b*, and at both in the respective forms, so as to cross their bends and stiffen and strengthen them.

45 In the modification illustrated by Figs. 7 and 7^x a blank for the metallic part is stamped or cut without waste from a strip of thin pliable metal in the form represented by Fig. 7^x, with longitudinal slits *x x* therein, which 50 are expanded laterally to form ventilating openings *d^x d^x*, Fig. 7, of ample size. Fig. 7 also illustrates the employment of a textile covering, *B^x*, cut of uniform width. It may be from a suitable tape and trimmed at the 55 ends after applying it.

In the modification illustrated by Fig. 8 the crimpler is of a larger size, and its large ventilating-openings *d^x d^x* are spanned by metallic bridges *g* integral with the remainder of the 60 metallic part. This figure may also illustrate stamping the crimpler flat from thin metal previously covered with textile fabric.

In the form illustrated by Figs. 9 and 9^x, which is the species of my crimpers selected 65 for specific claims, the crimpler made of sheet metal and textile fabric in the way first above

described has its clasp *c* extended in the form of a tongue, and its opening *d^x* at the opposite end of the flat crimpler is adapted to receive the same and coat therewith as a more secure 70 fastening device, as shown in Fig. 9; and to this end the textile covering is punched or cut from this catch-opening *d^x*, as represented. This does not destroy the main functions of 75 said covering as aforesaid, and a bridged ventilating-opening, *d*, is used in the lower leaf-frame from which the catch projects, and it is only here that bridging to confine the hair is essential in this form of my crimpers, as the opening in the upper leaf is spanned in 80 the closed crimpler by the extended clasp. This form of my crimpers is also provided with re-enforcing strips *f f*, Fig. 9^x, beneath its textile covering at its respective bends, or either of them, as aforesaid. 85

In the modification illustrated by Figs. 10 and 10^x the crimpler or its metallic part is made of round leaden wire, which may be wrapped with thread or the like, and is bent into the flat shape represented by Fig. 10^x for 90 the market, and in use is bent edgewise into its closed shape, (represented by Fig. 10,) apart from bending over its clasp *c*, which is done as in the form first described.

In the modifications represented by Figs. 11 95 and 11^x the crimpler or its metallic part is made of flat leaden wire in two pieces, laid together at one end side by side to form the clasp *c*, and lapped at the opposite end, as represented by *h*. It is bound with thread, 100 cord, or tape *i* at said clasp and lap, and also preferably at its "union" *b*, to unite the pieces, if the wire be covered with thread, as represented in Fig. 11, or without covering. Otherwise a textile covering, *B*, as first described, 105 may be applied to the wire with or without one or more of said bindings *i*, to unite the pieces, as well as to bridge its openings and give a desirable finish, as aforesaid, as represented by Fig. 11^x. 110

In the modifications illustrated by Figs. 12 and 12^x the crimpler or its metallic part is made of leaden wire, which may be either flat or round, bent so as to form said leaf-frames *a*, union *b*, and clasp *c*, with openings *d* of suitable size within the former, with the ends of the wire at the respective edges of said union, so as to be conveniently secured by a single wrapping, *i*, Fig. 12, if the crimpler is to be used with the wire bare, as shown in this figure, or simply wrapped with thread or cord, while the whole may be conveniently provided with a textile covering, *B*, if preferred, as represented by Fig. 12^x. 115 120

Other analogous modifications will suggest 125 themselves to those skilled in manufacturing such articles.

Having thus described my said improvement in hair-crimpers, I claim as my invention and desire to patent under this specification— 130

1. An improved hair-crimper having a pair

of metallic leaf-frames connected by a permanent flexible metallic union integral with said frames, substantially as herein set forth.

2. An improved hair-crimper having a pair 5 of metallic leaf-frames connected by a permanent flexible metallic union, and provided with a flexible metallic clasp integral with said frames, substantially as herein set forth.

3. An improved hair-crimper having a pair 10 of metallic leaf-frames, one of which is provided with a catch-opening, *d*', connected by a permanent flexible metallic union, and provided with a flexible metallic clasp, *c*', integral with said frames, adapted to interlock 15 with said catch-opening, substantially as herein set forth.

4. The combination, in a hair-crimper, of a metallic part comprising a pair of leaf-frames, a flexible union, and a flexible clasp, and a 20 covering of thin textile fabric united therewith by moisture-proof cement, substantially as herein set forth.

5. The combination, in a hair-crimper, of a metallic part comprising a pair of leaf-frames, a flexible union, and a flexible clasp, the lower 25 leaf-frame, from which said clasp projects, having a ventilating-opening therein, and a covering of thin textile fabric which bridges said ventilating-opening, substantially as herein set forth.

6. The combination, in a hair-crimper, of a metallic part comprising a pair of leaf-frames, a flexible union, and a flexible clasp made of very thin pliable sheet metal, and re-enforced at its bends, either or both, by strips of a 30 stronger pliable metal, and a covering of thin textile fabric outside of said re-enforcing strips, substantially as herein set forth.

EDWARD J. BROOKS.
